BY George Cook,

ATTORNEY.

UNITED STATES PATENT OFFICE.

JOHN P. STEPPE, OF NEW YORK, N. Y., ASSIGNOR TO S. STERNAU & CO.,
OF SAME PLACE.

DESIGN FOR A CHAFING-DISH.

SPECIFICATION forming part of Design No. 32,026, dated December 26, 1899.

Application filed November 28, 1899. Serial No. 738,598. Term of patent 3½ years.

To all whom it may concern:

Be it known that I, JOHN P. STEPPE, a citizen of the United States, residing at New York, borough of Brooklyn, county of Kings, 5 and State of New York, have invented and produced a new and original Design for a Chafing-Dish, of which the following is a specification, reference being had to the accompanying drawings, forming a part there-
10 of, in which—

Figure 1 is a plan view of a chafing-dish having my new design applied thereto. Fig. 2 is a side view thereof, and Fig. 3 a sectional view taken on the line 3 3 of Fig. 1.

15 The characteristic or principal feature of my design consists in the shape or contour of the dish, the body thereof being made in the form of a section of a sphere, from the upper edge of which extends outwardly a horizontal ring or flange and then a vertical ring or 20 flange, the upper extreme edge of the latter being curled or bent over, a handle extending outwardly from the dish, as shown.

Referring to the drawings, A represents the body of the dish, made in the form of a section of a sphere, and from the upper edge of which extends outwardly the seat or flange B, the latter being extended upwardly into a ring C, having its extreme edge bent or curled over, as shown at D. From the dish extends 25 outwardly the handle E.

There being no corners or sharp turns in the body of the dish, it has the appearance of being much shallower than is really the case.

Having fully described my invention, what 35 I claim as new, and desire to secure by Letters Patent, is—

The design for a chafing-dish, substantially as herein shown and described.

JOHN P. STEPPE.
